UNITED STATES PATENT OFFICE

2,540,177

IGNITION SYSTEM FOR FUEL BURNERS

Brooks H. Short and Charles E. Buck, Anderson,
Ind., assignors to General Motors Corporation,
Detroit, Mich., a corporation of Delaware

Application November 3, 1949, Serial No. 125,351

2 Claims. (Cl. 315—241)

1

This invention relates to apparatus for igniting fuel at the burner of an oil heater.

An object of the invention is to provide for igniting fuel by the passage electric current across a spark gap in sufficient quantity to provide the necessary heat for igniting fuel such as coal oil or Diesel fuel oil. This is accomplished by the use of an ignition coil by means of which a voltage is built up to cause discharge across the spark gap, this discharge providing a conducting path for the discharge of a previously charged condenser having capacity such that the current discharged by it is sufficient to ignite the fuel.

Further objects and advantages of the present invention will be apparent from the following description, reference being had to the accompanying drawings wherein a preferred embodiment of the present invention is clearly shown.

In the drawing, the single figure is a wiring diagram of the invention.

The apparatus includes a source of direct current such as battery 10 grounded at 11 connected by a switch 12 with a terminal 13 which is connected with the support 14 of a vibrating reed 15 having an armature 16 normally displaced from a magnet core 17 surrounded by a coil 18 connected with terminal 13 and with a resistance 19 which is grounded and with a contact 20 normally separated from an engaging contact 21 carried by the reed 15. Reed 15 also carries contacts 23, 25, and 27 normally spaced from and engageable respectively with contacts 22, 24 and 26. Contacts 24 and 26 are connected with the ends of primary windings 28 of a transformer T1 having the center tap 29 grounded. The secondary 30 of transformer T1 is connected at one end with a wire 33 and at the other with plate 39 of a tube 35 and with cathode 36 of tube 34. Cathode 37 of tube 35 is connected with ground and with a condenser 45 connected with wire 33. Plate 38 of tube 34 is connected with terminal 46 connected with condenser 44 connected with the wire 33. Wire 33 is connected through resistances 42a and 43 with elements 40 and 41 respectively of the tubes 34 and 35. Tubes 34 and 35 are cold cathode tubes having elements 40 and 41 which start electron emission.

Contact 22 and reed support 14 are connected with a condenser 50 connected with the primary winding 51 of a transformer T2. Secondary winding 52 of transformer T2 is connected with a spark gap 53 and with an auxiliary condenser 49 which is connected by a wire 48 and resistance 47 with output terminal 46 of the power supply

2

provided by transformer T1, tubes 34 and 35 and condensers 44 and 45.

The closing of switch 12 causes the current to flow from the battery 10 to the coil 18 thereby causing the armature 16 to move a distance into alignment with the core 17 such as to effect engagement of contacts 24, 25 and contacts 20, 21. When contacts 20, 21 engage the coil 18 is short circuited so that the reed 15 is permitted to swing in the other direction to effect engagement of contacts 22, 23 and 26, 27. The separation of contacts 20 and 21 having been effected coil 18 is energized again to repeat the operation. Therefore, as contacts 24, 25 and 26, 27 alternately engage current passes from the battery alternately into the halves of the primary winding 28 to obtain through the operation of the transformer T1 and the rectifier tubes 34 and 35 a relatively high voltage at terminal 53, for example 1500 volts D. C., which is sufficient for charging the condenser 49 in the time allowed.

While contacts 26, 27 are engaged, current flows in a direction indicated by arrow 28a in the left half of winding 28 thereby inducing a voltage in winding 30. Assuming that wire 32 is then positive, current flows through tube 35 and to one plate of condenser 45 in the direction of arrow 45a and by condenser action to wire 33. While contacts 24 and 25 are engaged, current flows in the direction indicated by arrow 28b in the right half of winding 28 and a voltage is induced in winding 30 such that wire 33 is positive; and current flows to one plate of condenser 44 in the direction of arrow 44a and by condenser action to tube 34 and to wire 32. A buffer condenser 31 absorbs transient voltages when vibrator contacts open. Since condensers 44 and 45 are in series and in assisting relation, the potential at terminal 46 is the sum of the potentials of condensers 44 and 45 and attains the required value to charge condenser 49.

While contacts 22, 23 are engaged, current builds up in winding 31. When contacts 22, 23 disengage, with the assistance of condenser 50 an abrupt reduction in current in winding 31 is effected and a voltage is induced in winding 52 (for example 20,000 volts) sufficient to break down the gap at the spark plug 53 and the energy of winding 52 discharges across the gap thereby providing a conducting path for the discharge of condenser 49 which has capacity such that the current discharged will supply heat sufficient to ignite the fuel. The discharge of condenser 49 continues until the voltage of that condenser decreases below the voltage (1000 volts for example)

sufficient to maintain the arc at the spark plug gap and will continue for a time after the energy of winding 52 has been dissipated.

Without the condenser 49, the discharge of ignition coil T2 appears as a pale blue spark of relatively short duration. With the condenser 49, discharging through the path established by the coil T2, there appears a reddish ball of fire. In other words, the spark is fatter and hotter.

While the embodiment of the present invention as herein disclosed, constitutes a preferred form, it is to be understood that other forms might be adopted.

What is claimed is as follows:

1. An ignition system for a fuel oil burner comprising a spark plug, an ignition coil having a secondary winding in series with the spark plug and having a primary winding, a current source, a vibrator operated by the current source for intermittently connecting the primary winding with the current source, a condenser in series with the secondary winding and the spark plug, a transformer having a secondary winding and a center-tapped primary winding, means operated by the vibrator for connecting the current source alternately with the halves of the primary winding of the transformer, two rectifier tubes having plates and cathodes, a connection between one end of the transformer secondary winding and the plate of one tube and the cathode of the other tube, parallel circuits connected with the other end of the transformer, one parallel circuit, including a condenser in series with the cathode of said one tube and the other parallel circuit including a condenser in series with the plate of said other tube whereby the potentials of the condensers in said parallel

circuits are in assisting relation, and a circuit including a resistance and all three condensers in series.

2. An ignition system for a fuel oil burner comprising a spark plug, an ignition coil having a secondary winding in series with the spark plug and having a primary winding, a condenser in series with the secondary winding and the spark plug, a transformer having a primary winding and a secondary winding, a direct current source, means for connecting the current source intermittently with the primary winding of the ignition coil and with the primary winding of the transformer, two rectifier tubes having plates and cathodes, a connection between one end of the transformer secondary winding and the plate of one tube and the cathode of the other tube, parallel circuits connected with the other end of the transformer, one parallel circuit, including a condenser in series with the cathode of said one tube and the other parallel circuit including a condenser in series with the plate of said other tube whereby the potentials of the condensers in said parallel circuits are in assisting relation, and a circuit including a resistance and all three condensers in series.
